UNITED STATES PATENT OFFICE.

FREDERICK GERKEN, OF NEW YORK, N. Y.

SPARK-PLUG.

1,253,584.

Specification of Letters Patent. Patented Jan. 15, 1918.

Application filed January 15, 1917. Serial No. 142,335.

To all whom it may concern:

Be it known that I, FREDERICK GERKEN, a citizen of the United States of America, and a resident of New York, in the county of New York and State of New York, have invented certain new and useful Improvements in Spark-Plugs, of which the following is a specification.

My invention relates to improvements in so-called "spark plugs," that is to say, sparking devices employed for igniting the charges of internal combustion engines, and also employed, sometimes, in other connections.

My invention consists in a novel construction of the electrodes or sparking terminals of such plugs, whereby a very high efficiency of operation is obtained, and whereby detrimental collection of carbon deposits and the like on the terminals of the plug is avoided.

The object of my invention is to improve the efficiency of spark plugs of the type described, and to avoid the troubles heretofore experienced with spark plugs.

I will now proceed to describe my invention with reference to the accompanying drawings, and will then point out the novel features in claims. In said drawings:

Figure 1 shows a side elevation of my improved spark plug;

Fig. 2 shows an end view thereof, on a larger scale than Fig. 1;

Fig. 3 a detail elevation and partial vertical section of the lower portion of the spark plug; and

Fig. 4 a view similar to Fig. 2 showing an alternative form of central electrode.

In the drawings, 1 designates the outer shell of the spark plug, provided, as usual, with a threaded lower portion 2 adapted to be screwed into the usual spark-plug port of an engine. The lower portion of the shell 1 is recessed, as indicated in Figs. 1 and 3, and as is common in many spark plugs of the present day.

3 designates one of the sparking terminals or electrodes of the plug; said terminal 3 being a ring or annulus connected to the portion 2 of the plug by struts or "ligaments" 4, there being, therefore, wide spaces 5 between the ring 3 and the lower portion 2 of the shell.

6 designates the other sparking terminal or electrode of the plug, having the form of a thin disk located within and spaced, as nearly as may be, uniformly away from the ring 3, and supported upon a central post 7.

It is to be understood that this post 7 is insulated in the usual manner from the shell 1, 8 (Fig. 1) designating a portion of the insulating material; and that this post 7 is provided at its upper end with means, such as a screw nut 9, whereby one conductor of an electric circuit may be connected to said post 7. I do not illustrate in detail the structure whereby the post 7 is insulated from the shell 1, as such construction forms no portion of the present invention, and ordinary means for effecting such insulation may be employed.

As shown in Fig. 2, the central electrode 6 is perforate; while as shown in Fig. 4, that central electrode, there designated by numeral 6^a, is imperforate. Whether a perforate or imperforate central electrode be employed, depends to a large extent upon the conditions obtaining in the engine in which the spark plug is used. It is found that if the engine be one having high compression and employing battery ignition (both of which conditions tend to produce high temperatures of the spark plug terminals) it is better to use a perforate central electrode, such as shown in Fig. 2; but if the engine in which the spark plug is used be one of moderate compression pressures, and one in which magneto ignition is used, an imperforate central electrode, such as shown in Fig. 4, may be employed to advantage.

Experience has shown that it is important that this central electrode 6 or 6^a be thin. A thickness of about ".03" has been found to work well. If this central electrode be too thick carbon deposit will form upon it to a detrimental extent; otherwise, no such deposits will form.

The form of the inner surface of the outer electrode 3 is important. As shown in Fig. 2, the inner surface of the electrode 3 is of scalloped form; that is to say, grooves or notches 10, with intervening blunt projections 11, are provided.

In the operation of this spark plug, the point at which sparking occurs varies greatly and changes continually; so much so that there appears to be a stream of sparks passing from the one electrode to the other, all around the plug; thereby giving a wide distribution of spark, such as greatly facilitates quick ignition and rapid flame propagation through the charge in the engine cylinder. Moreover, experience has shown that the same engine, fitted with this spark plug, tends to develop materially more

power than when fitted with an ordinary spark plug the terminals of which are two or more sparking points of ordinary construction. It has been found impossible 5 in practice to foul the spark terminals of this plug with carbon deposits, formed in the operation of the engine; carbon simply does not deposit, or, at least, does not remain deposited on the sparking terminals 10 3 and 6 to such an extent as to cause fouling, or to interfere with the operation of the engine. It appears that the grooves 10 in the inner surface of the outer sparking terminal, and very likely the openings 12 15 in the central electrode, have much to do with the prevention of formation of material carbon deposits on these terminals. It appears that the portion of the charge which, during the compression stroke, collects 20 in the chamber within the portion 2 of the plug, and then, upon ignition, blows out past the sparking terminals 3 and 6, passes as jets through the notches 10, clearing the sparking terminals of the plug; and 25 that the jets passing through these notches 10 have greater clearing efficiency than would be possessed by the thinner annular jet of such gases which alone would exist at such time between terminals 3 and 6, if the 30 notches 10 were not present. Such jets of gases passing between the terminals 3 and 6, and through the perforations of the central electrode, not only tend to clear such terminals of carbon deposit, but also seem 35 to cool such terminals somewhat; as is evidenced by the fact that, in a high compression, battery-ignition engine, the perforated central electrode 6 does not cause preignition, whereas the solid central electrode 6^a 40 shown in Fig. 4, may, in such engine, cause preignition; though the form shown in Fig. 4 will not cause preignition in an engine of a type with which it is intended to be used.

45 Furthermore, it has been found that engines fitted with spark plugs such as shown herein, start more readily and more quickly, under conditions which normally cause difficult starting, than when the ordinary 50 pointed spark plugs are used. So true is this, that it has been found that engines fitted with this spark plug will run very satisfactorily on kerosene, and without producing smoke, such engines being merely 55 started on gasoline and then immediately switched over to the use of kerosene, and this without any heating up run on gasoline.

60 It seems to be important that the inner electrode 6 shall be within the outer electrode 3, and not outside thereof, as has been the case in some prior spark plugs. Also, it seems to be important that the outer elec-

trode shall not be a tube continuous with the portion 2 of the spark plug; the separation 65 of the terminal 3 from the tubular portion 2 of the spark plug (except for the connecting ligaments 4) so that openings 5 are existent between portions 2 and 3 of the plug, seems to be essential.

70 It has also been found that, when using this spark plug, a leaner mixture may be used in the engine than when ordinary spark plugs are used. This results in great economy in the use of fuel.

75 This spark plug is an improvement upon the plug of the patent to Walter No. 812,622, and embodies improvements over that Walter plug which have been found to be important in practice and to give greatly 80 improved results.

What I claim is:—

1. In a spark plug, the combination with a shell, having within it a pocket and carrying an outer ring-like spark-terminal 85 grooved interiorly and supported by but spaced away from such shell by connecting ligaments providing openings between the main portion of the shell and the said ring terminal, of another spark terminal within 90 said ring terminal but spaced away therefrom and suitably supported, and having the form of a thin disk.

2. In a spark plug, the combination with a shell, having within it a pocket and carrying an outer ring-like spark-terminal 95 grooved interiorly and supported by but spaced away from such shell by connected ligaments providing openings between the main portion of the shell and the said ring 100 terminal, of another spark terminal within said ring terminal but spaced away therefrom and suitably supported, and having the form of a thin disk, said disk being perforate.

105 3. A spark plug provided with two spark-terminals, one of which is a ring and the other of which is a thin disk located within that ring, said ring having an interior scalloped surface.

110 4. A spark plug comprising a body portion and two spark-terminals supported therefrom and insulated one from the other, one of said terminals being a ring spaced away from the body of the plug and having a scalloped interior surface, the other of 115 said terminals being a thin disk located within said ring.

120 In testimony whereof I have signed this specification in the presence of two subscribing witnesses.

FREDERICK GERKEN.
